UNITED STATES PATENT OFFICE.

NELSON E. RABER, OF AKRON, OHIO, ASSIGNOR TO THE B. F. GOODRICH COMPANY, OF NEW YORK, N. Y., A CORPORATION OF NEW YORK.

CUTTING MACHINE.

Application filed May 6, 1921. Serial No. 467,475.

To all whom it may concern:

Be it known that I, NELSON E. RABER, a citizen of the United States, residing at Akron, in the county of Summit and State 5 of Ohio, have invented a certain new and useful Cutting Machine, of which the following is a specification.

This invention relates to machines for cutting sheet material, such, for example, 10 as the uncured, rubberized fabric used in the manufacture of rubber footwear, to produce formed pieces or units. The embodiment herein illustrated and described is adapted to fold and cut a strip of rubberized fabric to form boot-straps.

The stock usually comes to the machine in rolls wherein a strip of the rubberized fabric stock is interwound with a "liner." 15 The stock rolls are made up at the calendar 20 and in cooling the stock shrinks slightly within the roll. Because of this, and because the tension of the stock and liner respectively during the winding operation may differ, the stock, when withdrawn from 25 the roll at the cutting machine, may vary in the yardage given off relative to the yardage of the liner.

While the stock is advanced intermittently and cut into units, it is desirable that the 30 liner be rerolled for further use, with uniform tension notwithstanding the intermittent motion of the stock and the different yardages given off by the stock and the liner, and that the stock be advanced to the 35 cutter with uniform tension.

The main objects of my invention are to provide a simple, automatic and accurate mechanism for cutting sheet material into formed units and, in the case of flexible material such as rubberized fabric and a cloth liner, to provide improved guiding means and tensioning and rewinding means.

Of the accompanying drawings:

Fig. 1 is a side elevation, with a part 45 broken away, of a preferred embodiment of my invention.

Fig. 2 is a detailed side view, with parts broken away, of a part of a feeding and cutting mechanism.

50 Fig. 3 is a cross-sectional view on the line 3—3 of Fig. 1.

Fig. 4 is a partial plan view showing the fabric-folder, feed-roller and cutting block.

Fig. 5 is an end view of a part of the folder or plaiter.

55

Fig. 6 is a plan view of the cutting-block assembly.

Fig. 7 is a reverse plan view of the cutting-die.

60

Fig. 8 is an elevation, partly in section, of the cutting-block assembly as viewed from the delivery end of the machine.

Fig. 9 is a detailed view partly in section, of the die-holder.

65

Fig. 10 is a plan view of the cut fabric strip, showing the design of the cut produced by the die.

Fig. 11 is a plan view of the fabric guiding and tensioning apparatus.

70

Fig. 12 is a plan view of the liner-tensioning and rewinding apparatus.

Referring to the drawings, 10 is a frame, 11 is a stock roll loosely journalled thereon, 12, 12^a, 13, 13^a and 14, 14^a are guide rollers loosely journalled on brackets secured to

75

said frame, the pair of rollers 13, 13^a being interposed between the other two pairs of rollers just mentioned and having their axes transverse to theirs. 15 is a plaiting device, 16 is a feed roll, 17 is a loosely-journalled,

80

intermittent-pressure roll co-operatively associated therewith through an opening in the frame 10. 18 is a die-cutter, 19 is an endless-belt carrier, and 19^a is a floating roller thereon. 19^b is a belt tightener for

85

the belt-carrier 19. 20 is a liner. 21, 22, 22^a, 23 and 23^a are guide-tension devices secured to the frame 10, 24 is a liner rewinding roll,

90

25 is an electric motor, and 26, 27, 28, 29 is a speed-reduction assembly comprising a large belt-wheel 27 and a small sprocket 28 secured to their common shaft 29 which is journalled in brackets 26 mounted upon

95

the frame 10. 27^a is a belt between the motor 25 and the wheel 27.

The plaiting apparatus 15, shown in detail in Figs. 4 and 5, comprises a pair of overhanging guide plates 30, 30 secured to the frame 10, each formed with a series of holes 31, 31 through the over-hung portions; a

100

plate 32 formed with side flanges at its base slidably interfitting between said plates 30 and between their overhanging portions and the frame 10, said flanges being formed with holes adapted to register with the holes 31 in the plates 30; a folding-eye 33 secured upon

105

said plate 32; a plaiting sleeve 34 also secured on said plate 32; and dowel pin 35 interfitting with registered holes in one of the plates 30 and the plate 32. 135, 135 are 5 pins mounted upon the base of the die cutter and adapted to serve as side guides for the folded strip as it passes to the cutter.

Referring to the arrangement of gears and mechanism for driving the several parts 10 of the machine, and with particular reference to Figs. 2 and 3, 36, 36^a are brackets depending from the frame 10 and provided with bearings for shafts 37, 38 extending through said brackets and protruding therefrom at both ends. 39 is a large sprocket secured upon a common hub 40 with a small sprocket 41, said common hub being loosely journaled upon the protruding end of shaft 38 outside of the bracket 36^a, the smaller 15 sprocket 41 being connected by a sprocket-chain 41^a with a large sprocket 42 secured upon the corresponding end of shaft 37, and the larger sprocket 39 being connected with the small sprocket 28, Fig. 1, by a sprocket 20 chain 39^a. 43 is a sprocket secured to the shaft 37 between the brackets 36, 36^a and connected by a sprocket-chain 43^a with a sprocket 44 secured in common with belt-wheels 45 and 46 upon a hub 47, said hub being 25 loosely journaled upon the shaft 38. The feed-roller 16 is secured to the shaft 37. Secured upon the other end of the shaft 37 from the sprocket 42, and outside of the bracket 36, is a spur-gear 48, and in alignment therewith, secured to the corresponding 30 end of the shaft 38, is a spur-gear 49. Intermeshed between gears 48 and 49 is an intermediate spur-gear 50, journaled upon the elbow of an arm 51, one end of said arm being pivoted upon the shaft 37 between the gear 48 and the bracket 36, and the other end of said arm 51 being provided with a clamping bolt 52 slidably mounted in an arcuate slot 53, concentric with the shaft 37, in the bracket 36. 54 is a cam wheel secured upon the shaft 38. 55 is an L-shaped lever fulcrumed at 56 on the bracket 36, its outer end, being secured to a vertical link 57 by an adjustable bearing member 57^a, and the upturned toe of the L being pivoted to a vertical push-rod 58. The heel of the L is provided with a cam roller 59 associated with the cam-wheel 54.

The intermittent-pressure roll 17 is secured upon a spindle 17^a which is journaled in journal blocks 60, 60^a, which are vertically slidable in guideways formed in standards 61 and 61^a, mounted upon the frame 10 above the feed-roll 16, the journal blocks 60, 60^a overhanging or extending laterally of the machine beyond said standards 61, 61^a.

Compression springs 62 are interposed in said guide-ways between said journal blocks 60 and adjustable flanged stud-bolts 63 are

mounted in bridge-plates 64 secured to the tops of the standards 61, 61^a across the guide-ways. The overhanging end of the journal block 60^a at the back of the machine rests upon a stud-bolt (not shown) 70 threaded into the base of the standard 61^a and the overhanging end of the journal block 60 at the front of the machine rests upon the top of the push-rod 58.

The die cutter 18 comprises a platen 65, 75 the back end of which is connected with a bracket 66, upon the frame 10 by a pair of links 67, 67, and the front end of which is hinged to the top of the vertical link 57 of the cam lever 55.

68 is a compression coil spring upon the link 57 and interposed between the platen 65 and the frame 10. The platen 65 is formed with a downwardly-extending ear 69 at its middle, pivotally connected with a die block 70 formed with vertical holes 71 adapted to receive dowel pins 72 secured upon the frame 10, and with spring-holding recesses 73 in its lower side. The die 74 is formed with a base having holes there-through and is secured to the under side of the block 70 by screws 76 with the holes of its base concentric with the spring-holding recesses 73 in said block. 77 is a pressure foot formed with a slot, not shown, registering with the die 74 and with threaded legs or stems 78 which extend through the holes of the die base 75 and are provided with spring-engaging nuts 78^a. 79 are compression springs within the recesses 73, bearing 80 upon said nuts. 80 is a cutting block under the die.

The liner rewinding apparatus comprises guiding and tensioning devices 21, 22, 22^a, 23 and 23^a, a loosely-journaled, vertically-slidable liner-roll 24; a loosely journaled, vertically-slidable weight roller 81 superimposed thereon; and peripheral drive rollers 82 and 83, the roller 82 being smooth surfaced and the roller 83 knurled.

84 is a belt wheel connected by a belt 84^a with the belt-wheel 45. The peripheral drive-rollers 82 and 83 and belt-wheel 84 are secured upon respective shafts journaled upon the frame 10 and extending beyond their journals at one end, their extensions having secured thereon intermeshed spur-gears 85, 86 and 87, respectively. 88 is a cam latch adapted to engage the spindle of the weight roller 81 when the latter is raised out of operative position.

The guide-tension devices for the liner comprises a cylindrical, non-rotating member 23 secured to the frame 10 in alignment with the stock roll 11 and preferably in a direction therefrom approximately at right angles to the direction of the fabric strip 11^a adjacent the stock roll in order that the liner and the fabric may be separated promptly upon leaving the stock roll; an 120

aligned series of cylindrical, non-rotating members 21^a, 21^b, 21^c, 21^d, 21^e and 21^f and a bracket-like snubbing member 22, upon another part of the frame; a vertically disposed guide member 22^a pivoted at 22^b and provided with an adjustment screw 22^c adapted to adjust it laterally to align the liner with the rewinding roll 24; and a cylindrical, non-rotating member 23^a secured to 10 the frame 10 close to the peripheral drive roller 82 and parallel therewith.

In the operation of the machine, the stock roll 11, carrying a strip of rubberized fabric 11^a and a cloth liner 20 wound thereon in 15 alternate convolutions is mounted in its bearings, as shown in Figs. 1 and 11, the fabric strip is threaded through the guide-rolls 12, 12^a, 13, 13^a and 14, 14^a, through the folding-eye 33 and the plaiting sleeve 34 of 20 the plaiting device 15, between the feed roller 16 and the intermittent-pressure roller 17 superimposed thereon, between the die 74 and the cutting block 80, and between the belt-carrier 19 and the floating pressure roller 19^a supported thereby.

The liner 20 is threaded through the series of guide-tension devices 23, 21, 22, 22^a and 23^a, as shown in Figs. 1 and 12, and its end secured upon the liner roll 24, which rests 30 upon the peripheral-drive rollers 82 and 83. The weight-roller 81 is released from the hook 88 and allowed to bear upon the top of the liner roll 24, pressing it down against the drive rollers 82 and 83. The tension and 35 the amount of snubbing effect upon the liner 20 may be varied by changing its devious course through the series of members 21 (a, b, c, d, e and f).

The motor 25 is then started, driving, in 40 the order given, the belt-wheel 27 and the sprocket 28 therewith; from the latter, the large sprocket 39 and with it the small sprocket 41; from the latter the large sprocket 42 and with it, upon their common 45 shaft 37, the sprocket 43, the feed roller 16 and the gear 48; from the sprocket 43 the sprocket 44 and the belt wheels 45 and 46 therewith, from the gear 48 the intermediate gear 50 and the gear 49, and with the last-named the shaft 38 and the cam wheel 54 thereon; from the belt wheel 45 the belt wheel 84 and with it the gear 86, and, from the latter, the gears 85 and 87 in the same direction, and with them the peripheral 55 drive rollers 82 and 83 respectively, and from them the liner roll 24 and the weight roll 81; from the belt wheel 46 the belt carrier 19 and the weight roller 19^a thereon.

The intermittent pressure roller 17 presses 60 the fabric strip 11^a down upon the top of feed roller 16, causing it intermittently to advance therewith, drawing the fabric strip from the stock roll 11 through the folding-eye 33 and the plaiting sleeve 34 of the device 15, by which the fabric is folded over

to the middle from both sides, to be pressed together between the rolls 16 and 17. As the folded fabric strip advances, as stated, with the periphery of the feed roller 16, it is thereby fed to the cutting device 18. 70 With each revolution of the cam wheel 54 the link 57 is jerked downward, actuating the die-cutter 18 and simultaneously the intermittent pressure roller 17 is raised against the spring 62 by the push-rod 58 acting against the journal block 60, momentarily releasing the pressure of the fabric strip against the feed roller 16 and thus stopping the feed of the folded fabric strip to the die-cutter, while the latter is operating upon the strip. 75

The form of the die may be such that the fabric strip is not completely severed, a few strands remaining uncut at the middle of the strip, to be easily broken by hand later. 80 Such strands temporarily hold the fabric units lightly together in order that the stock may be drawn through the cutter by the belt carrier and the floating roller 19^a, 85 cooperating therewith. While the motion of the belt carrier 19 is constant, it has been found that the slippage of the chain of fabric units thereon and their elasticity is sufficient to prevent breakage due to the momentary stopping of the fabric strip 90 under the pressure foot 77.

The construction of the die cutter 18, as described, is such that as the platen 65 is lowered by the link 57, against the action of the compression-spring 68, the die-holding block 70, being pivoted to the platen and guided by the dowel pins 72, descends evenly upon the cutting block 80. The pressure foot 77 first comes into yielding contact with the fabric strip 11^a owing to the action of the springs 79, holding the strip firmly in place against the cutting block 80, and thereafter the die 74 passes through the registered slot in the pressure foot and cuts the fabric held thereunder. When the reaction of the spring 68 raises the platen 65, the pressure foot 77, due to the action of the spring 79, continues its pressure on the fabric until the die has been withdrawn therefrom. 105

Meanwhile the liner 20 is rewound upon the roll 24 under suitable tension, the ratios of the several belt wheels, sprockets and gears being such that the peripheral speed of the rolls 82 and 83 is sufficiently greater than that of roll 16 to compensate the difference between the yardage of the fabric strip and that of the liner, as above mentioned. The unwinding of the roll 11 and consequently the release of the liner 20 is intermittent because of the periodic, momentary lifting of the pressure roll 17 from the feed roll 16, but the irregularities in the unwinding of the liner 20 due to such intermittence of roll 11 and to the non-uniform shrink- 110 115 120 125 130

age of the fabric strip is compensated by slippage of the peripheral drive rollers 82 and 83. The stoppage of roll 11, or a reduced yardage of liner released therefrom, 5 results in a tightening of the liner 20 between the stock-roll 11 and the guide-member 23 which, through the snubbing effect of devices 21 and 22, results in greatly increased tension in the liner as it passes the 10 member 23^a, without greatly affecting the movement of the roll 11. The tension in the liner 20 is thus magnified or multiplied as it passes from the stock roll 11 to the liner rewinding roll 24.

15 Such increased tension, due to the said snubbing effect, results in slippage of the rolls 82 and 83 upon the liner 20, permitting the movement of the latter to lag in keeping with the movement of the roll 11, 20 without unduly affecting the movement of the latter. While the roller 83 is knurled, to enable it to exert driving force upon convolutions of liner within the roll and to compensate for its small area of contact 25 with the liner, its contact area is so limited that slippage is not prevented by its knurled tread when the relatively high tension is produced in that region by the relatively small increase of tension in the liner anterior 30 to the snubbing devices.

The guide rollers 13 and 13^a, being journaled on axes transverse to those of the rollers 12, 12^a, 14, 14^a effectively align the fabric strip for the feed roll 16 and die 35 cutter 18, notwithstanding the flimsy character of the fabric which unsuits it to be guided by side-guide rollers alone, although the latter may be added for slight corrections of alignment. After passing between 40 the rollers 13, 13^a, the fabric may be returned to its horizontal position with either side up, as it is threaded through the rollers 14, 14^a, this arrangement of rollers being a 45 convenient device for turning the fabric between the stock roll and the cutter.

The plaiting device 15 may be adjusted from and toward the feed roll 16 to affect the character of the fold produced in the fabric by means of the dowel pin 35 and the 50 registerable holes 31 in the guide plates 30 and the holes in the side flanges of the sliding plate 32 which carries the folding-eye 33 and sleeve 34.

The application of the pressure-foot 77 55 to the fabric, and the lifting of it therefrom may be suitably synchronized with the lifting of the intermittent pressure roll 17 by adjustment of the nuts upon the legs 78 of the pressure foot and adjustment of the 60 bearing member 57^a.

The length of fabric fed between cutting operations may be varied by substituting a larger or smaller gear for gear 50, the arm 51 being adjusted in the slot 53 to hold such 65 substituted gear in proper position to inter-

mesh with gears 48 and 49. Pressure of the roller 17 upon the fabric as it passes over the feed roll 16 is varied by adjustment of the threaded, flanged spring studs 63. The proper alignment of the liner as it passes to 70 the liner rewinding roll 24 is secured by adjustment of the guide member 22^a by means of the screw 22^c. The liner, like the stock, is unsuitable because of its flimsy character to 75 be guided by side rollers, but the guide 22^a, by reason of its vertical position, is adapted to guide the liner by bearing against its flat face, the member 22 having turned the liner substantially into a vertical plane.

Various modifications may be resorted to 80 without departing from the scope of my invention and I do not wholly limit my claims to the construction shown.

I claim:

1. In a cutting machine the combination 85 of a stock roll and a mounting therefor, a cutter, means for feeding stock from said roll to said cutter, a liner rewinding roll, means for frictionally driving said rewinding roll, and a tension device adapted to produce in the liner adjacent said rewinding roll a tension varying widely in response to relatively small variations in the tension of the liner anterior to said tension device.

2. In a cutting machine the combination 90 of means for supporting a supply of stock, a cutter, means for intermittently feeding stock from said supporting means to said cutter, a liner rewinding roll, means for frictionally driving said rewinding roll, and a tension device adapted to produce in the liner adjacent said rewinding roll a tension varying widely in response to relatively 95 small variations in the tension of the liner anterior to said tension device.

3. In a cutting machine the combination 100 of a stock roll and a mounting therefor, a cutter, means for feeding stock from said stock roll to said cutter, a liner rewinding roll, means for frictionally driving said rewinding roll, and a snubbing device for the liner adapted to magnify the tension in the latter as it passes from said stock roll to said liner rewinding roll.

4. In a cutting machine the combination 110 of means for supporting a supply of stock, a cutter, means for intermittently feeding stock from said supporting means to said cutter, a liner rewinding roll, means for frictionally driving said rewinding roll, and a snubbing device for the liner adapted to magnify the tension in the latter as it passes from said stock roll to said liner rewinding roll.

5. In a cutting machine the combination 125 of a stock roll and a mounting therefor, a cutter, means for feeding stock from said stock roll to said cutter, a liner rewinding roll, means for frictionally driving said rewinding roll, and a liner tensioning device 130

- comprising a series of guide tension members adapted to be threaded in different combinations to increase or decrease their tensioning effect.
5. In a cutting machine the combination of means for supporting a supply of stock, a cutter, means for intermittently feeding stock from said supporting means to said cutter, a liner rewinding roll, means for 10 frictionally driving said rewinding roll, and a liner tensioning device comprising a series of guide-tension members adapted to be threaded in different combinations to increase or decrease their tensioning effect.
15. 7. In a cutting machine the combination of a stock roll and a mounting therefor, a cutter, means for feeding stock from said stock roll to said cutter, a liner rewinding roll, means for peripherally driving said rewinding roll, and a tension device adapted to produce in the liner adjacent said rewinding roll a tension varying widely in response to relatively small variations in the tension of the liner anterior to said tension device.
20. 8. In a cutting machine the combination of means for supporting a supply of stock, a cutter, means for intermittently feeding stock from said supporting means to said cutter, a liner rewinding roll, means for peripherally driving said rewinding roll, and a tension device adapted to produce in the liner adjacent said rewinding roll a tension varying widely in response to relatively 25 small variations in the tension of the liner anterior to said tension device.
25. 9. In a cutting machine the combination of a stock roll and a mounting therefor, a cutter, means for feeding stock from said stock roll to said cutter, a liner rewinding roll, a smooth roller and a knurled roller adapted to support said rewinding roll and peripherally drive the same, and a tension device adapted to produce in the liner adjacent said rewinding roll a tension varying 30 widely in response to relatively small variations in the tension of the liner anterior to said tension device.
35. 10. In a cutting machine the combination of a stock roll and a mounting therefor, a cutter, means for feeding stock from said stock roll to said cutter, a liner rewinding roll, a smooth roller and a knurled roller adapted to support said rewinding roll and peripherally drive the same, yielding means for pressing said rewinding roll against said supporting rollers, and a tension device adapted to produce in the liner adjacent said rewinding roll a tension varying 40 widely in response to relatively small variations in the tension of the liner anterior to said tension device.
45. 11. In a cutting machine the combination of means for supporting a supply of stock, a cutter, means for intermittently feeding stock from said stock roll to said cutter, a liner rewinding roll, means for frictionally driving said rewinding roll, and a liner tensioning device comprising a series of non-rotating tension members adapted to be threaded in different combinations to increase or decrease their tensioning effect.
50. 12. In a cutting machine, the combination of means for supporting a supply of stock, a reciprocating cutter adapted substantially to sever the stock at intervals but to leave a strip of uncut stock connecting successive units, frictional means for lightly pulling the string of units from said cutter, a continuously driven feed roll for feeding the work from said stock supporting means to said cutter, a presser roller adapted to hold the work in frictional contact with said feed roll, and means for concurrently actuating said cutter and retracting said presser roller from said feed roller so as to permit the latter to slip with relation to the work.
55. 13. In a cutting machine the combination of means for supporting a supply of stock, a cutter, a feed roller and means for imparting rotary movement thereto, a presser roller associated therewith, means for intermittently retracting the latter from said feed roller to interrupt the feed of stock to said cutter, a liner rewinding roll, means for frictionally driving said rewinding roll and a tension device adapted to produce in the liner adjacent said rewinding roll a tension varying widely in response to relatively small variations in the tension of the liner anterior to said tension device.
60. 14. In a cutting machine the combination of means for supporting a supply of stock, a cutter, means for feeding stock from said supporting means to said cutter, a liner rewinding roll, rollers adapted to support said rewinding roll and peripherally drive the same, and a liner tensioning device comprising a series of non-rotating tension members adapted to be threaded in different combinations to increase or decrease their tensioning effect.
65. 15. In a cutting machine the combination of a stock roll and a mounting therefor, a cutter, means for feeding stock from said stock roll to said cutter, a liner rewinding roll, rollers adapted to support said rewinding roll and peripherally drive the same, and a snubbing member adapted to turn the liner into a plane transverse to the axis of said liner rewinding roll.
70. 16. In a cutting machine the combination of a stock roll and a mounting therefor, a cutter, means for feeding stock from said stock roll to said cutter, a liner rewinding roll, means for frictionally driving said re-

winding roll, and a liner tensioning device comprising a series of guide-tension members adapted to be threaded in various combinations to vary their tensioning effect, and a 5 snubbing member.

17. In a cutting machine the combination of a stock roll and a mounting therefor, a cutter, a feed roller adapted to draw stock from said stock roll and feed it to said cutter, 10 and a guide roller journalled on an axis transverse to that of said feed roller.

18. In a cutting machine, the combination of means for supporting a supply of stock, 15 means for cutting said stock, rotary means for advancing said stock to said cutting means, a lever connecting said rotary means with said cutting means, and means for actuating said lever to simultaneously interrupt the advance of said stock and actuate 20 said cutting means.

19. In a cutting machine the combination of a feed roll, a presser roll associated therewith, a cutter, a lever operatively connecting one of said rolls with said cutter, and means 25 for intermittently operating said lever to simultaneously separate said rolls and actuate said cutter.

20. In a cutting machine the combination of a pair of parallel shafts, a feed roller secured to one of said shafts, a cam wheel secured to the other of said shafts, positive 30 driving means connecting said shafts, a presser roller associated with said feed roller, a cutter and means actuated by said cam wheel for intermittently and simultaneously retracting said presser roller from 35 said feed roller and operating said cutter.

21. In a cutting machine the combination of means for supporting a supply of stock, 40 a cutter adapted substantially to sever the stock transversely at intervals but to leave a strip of uncut stock longitudinally connecting successive units, means for lightly pulling the string of units from said cutter, and 45 means positioned operatively between said stock-supporting means and said cutter for feeding the work forward to the latter and constituting the only means of substantial force for so feeding the work.

22. In a cutting machine the combination of means for supporting a supply of stock, a reciprocating cutter adapted substantially to sever the stock transversely at intervals 50 but to leave a strip of uncut stock longitudi-

nally connecting successive units, means for 55 lightly pulling the string of units from said cutter, and means positioned operatively between said stock-supporting means and said cutter for intermittently feeding the work forward to the latter in timed relation to the 60 action of said cutter and constituting the only means of substantial force for so feeding the work.

23. In a cutting machine the combination of means for supporting a supply of stock, 65 a cutter adapted substantially to sever the stock transversely at intervals but to leave a strip of uncut stock longitudinally connecting successive units, means for lightly pulling the string of units from said cutter, and means positioned operatively between said stock-supporting means and said cutter for feeding the work forward to the latter and constituting the only means of substantial 70 force for so feeding the work, the aforesaid 75 pulling means comprising a member adapted to pull the string of units by sliding contact therewith.

24. In a cutting machine the combination of a stock roll and a mounting therefor, a feed roller and means for imparting rotary movement thereto, a presser roller associated therewith, means for intermittently retracting the latter from said feed roller, a cutter adapted to receive stock from said feed roller, a liner rewinding roll, means for frictionally driving said rewinding roll, and a liner tensioning device comprising a 80 series of guide-tension members adapted to be threaded in various combinations to vary 85 their tensioning effect, and a snubbing member positioned operatively between said guide-tension members and said rewinding roll.

25. In a cutting machine the combination 90 of a plaiter, a pair of rolls adapted to press the stock after it has been folded by said plaiter, said plaiter being adapted to be adjusted from and toward said pair of rolls to vary the character of the fold, means for 95 transversely cutting the folded stock at measured intervals, and common means for actuating said cutter and spreading apart 100 said rolls so as to interrupt the feed of the work.

In witness whereof I have hereunto set my hand this 23 day of April, 1921.

NELSON E. RABER.
